GUIDE TO LOS ANGELES
INTRODUCTION.

This book contains the principal streets in Los Angeles City; street numbers, names and location of hotels etc. car lines that go to or near the places and streets mentioned; indicating the streets at which to get on and off the car and the distance to street or place desired. In giving the distance

UNITED STATES PATENT OFFICE.

CHARLES W. MERRILL, OF LOS ANGELES, CALIFORNIA.

ROUTE-INDEX.

No. 839,399.

Specification of Letters Patent.

Patented Dec. 25, 1906.

Application filed June 16, 1905. Serial No. 265,510.

To all whom it may concern:

Be it known that I, CHARLES W. MERRILL, a citizen of the United States, residing at Los Angeles, in the county of Los Angeles, State of California, have invented a new and useful Route - Index, of which the following is a specification.

An object of this invention is to provide means whereby a person may readily ascertain the most convenient route by which to reach a given destination from a given place.

Another object is to provide a complete route-directory in the most condensed form, also to give the information in the most convenient form for ready reference.

Another object is to provide means for ascertaining at a glance the connections between one line and other lines of travel.

Another object is to provide condensed means for readily ascertaining the distance from one place to another by a determined route and also the distance traveled by car and that to be traveled afoot or otherwise.

A further object of this invention is to provide means for readily ascertaining the shortest and best route leading from one point to another, it not being necessary for a person provided with an index arranged according to the principles of this invention always to refer to or pass by the same point or locality in going from one place to another.

One of the most important objects of this invention is to provide indexing means adapted to be applied to city directories now in use without altering the arrangement or materially increasing the size of such directories.

I will illustrate the principle of this invention by referring to an application of the same covering the street-railways, the streets, residences, public buildings, and places of interest to be reached in a city. In cities where there is a concentration of car-lines at some central locality a graphic list of car-lines and their connections may be made in the form of a map.

The accompanying drawings illustrate the invention as applied to a route-index for a modern city.

Figure 1 is a fragmental view of an open book provided with a route-index embodying this invention, showing the appearance of a page thereof which contains a portion of the thoroughfare-list. Fig. 2 shows a continuation of the thoroughfare-list. Fig. 3 is a

broken fragmental view showing one of the routes of the route-list on the right side and on the left side an index to be used in referring to the routes contained in said list. Fig. 4 and the left portion of Fig. 5 show a continuation of the route - list. The right page shown in Fig. 5 illustrates the feature of my invention which adapts it to be applied to any city directory.

In constructing this index I provide a number of lists—as, for example, a thoroughfare-list A for the streets, a route or car-line list B, and a place-list C. The drawings show a directory containing a list of numbered route-designating headings 1, each followed by a series of house-numbers 2 of the streets along which the route extends; said house-numbers being arranged in progressive order from one end of the route and designating the points where the route is intersected by cross-streets, whether numbered dwellings are actually located at such points or not. Each of the numbered route-designating headings 1 constitutes means at the head of the respective lists B for designating the route of travel to which such list B appertains. 3 designates the names of said cross-streets, there being a row of numbers 4 consecutively numbering the same. Street-numbers 45 indicate the house-number of each cross-street at the point it intersects the route, said numbers 45 being placed opposite the names 3 of the cross-streets referred to or otherwise definitely positioned to associate them with the names of said cross-streets.

30 designates the aforementioned names of the streets along which the route extends or the car runs, said names being desirably distinguished by being printed in a different style of type. The numbers 4, which are employed mainly to designate streets crossing the route, as already stated, may also be regarded as indicating the stations or points where the car stops. The numeral 1 may indicate a station at the end of the line from which the numbers start.

5 designates the headings contained in the list A of the street-designating headings. The street-designating headings 5 are followed by names 51, designating the cross-streets.

55 designates street-numbers of the street named by the heading, said numbers indicating the points at which the cross-streets 51 opposite thereto are intersected.

50 designates numbers arranged in a series of pairs following each of the street-designating headings 5, there being a pair of numbers placed opposite to each of the cross-streets

- 5 51. 5^a designates one of said pair of numbers, said number referring, as hereinafter described, to one of the route-designating headings: 5^b designates the other of said pair of numbers, which refers to a number of 10 the aforementioned row of numbers 4, which refer to cross-streets in list B.

Throughout the various lists 52 designates numbers in parentheses, which indicate the number of blocks to be walked or otherwise 15 traveled before reaching a car-line in going to a given place or after leaving the car traveling on the route taken. Said numerals may indicate the nearest whole number of blocks.

- Reference is now made to the left page 20 shown in Fig. 4 to explain a further detail of the manner in which I prefer to arrange the index. The heading "Car-line 17" is followed first by the name of said car-line and then by the name ("Adams W.") of the first 25 street along which the car runs from the starting-point. The figure "1" of the ordinal 4 at the left of said name may be used alone to designate the starting-point or first station, which in the illustration given in Fig. 30 4 is at the intersection of West Adams and Arlington streets, being at 2300 Adams street, as indicated by the ordinals 2, and at 2600 Arlington street, as indicated by the ordinals 45. It is immaterial what number the 35 ordinals 4 begin with if said numbers are arranged in a series ascending in regular order. Referring still to Fig. 4, the numbers 2 down to and including "1700" (which is opposite "Normandie S.") are all house-numbers of 40 Adams street. Likewise "2400" at the left of "Twenty-fourth" does not refer to Twenty-fourth street, but to 2400 South Normandie street.

Car-line 17 is described as running from 45 Arlington street along West Adams street, across Cimmaron, Hermosa streets, &c., to South Normandie street, thence on South Normandie street across Twenty-fifth street to Twenty-fourth street, thence along Twenty-

- 50 fourth street.
- Referring to the place-list C, 6 designates the appropriate heading therefor, hotels being referred to in the present instance. 60 designates names of places (or of business 55 houses or individuals in other applications of the invention) to be located, and 61 refers to printed matter constituting means for designating the location of said places on the streets where the same are situated. The 60 numbers 5^a, 5^b, and 52 are also used in connection with the place-list C to indicate the route to be taken and the distance to be traveled after leaving the car in going to or before reaching the car in going from the points 65 60.

65 For example, assume the inquirer to be at the

Angelus hotel and he wishes to reach a place on Arlington street. He will turn first to list A and, finding the name "Arlington," (see Fig. 2,) he will run his eye along the numbers 51 in the left-hand column until he finds the 70 number approximating the number on Arlington to which he wishes to go. For example, we will assume that he wishes to go to 2525 Arlington. He will see by the list that Adams street is the street having the car-line 75 crossing which is nearest to the number on Arlington which he wishes to reach, because Adams crosses Arlington at 2600. Then reading the numbers to the extreme right he will see that car-line 17 is the car-line he 80 wishes to take and that he should get off the car at station No. 2 on that car-line. Then he may turn to the index C of hotels, where he finds that his nearest station to car-line 17 is 74 and that the Angelus hotel is one block 85 from No. 74 on car-line 17. By reference to the car-line list 17 he finds that No. 74 (see right-hand page, Fig. 4) is at the corner of Third and Spring streets, being No. 200 Third street. As the Angelus hotel is at the corner 90 of Fourth and Spring, he will walk one block along Spring street to Third street and there will take a car on line 17—namely, the West Adams street and Boyle Heights car on the Los Angeles Interurban car-line. He will 95 also have noted from the list under the heading "Car-line 17" that his car runs directly to the corner of Adams and Arlington and that he will there be at No. 2300 Adams and No. 2600 Arlington. In each instance a number 100 5^a found in list A or C is a number used in numbering a route-designating heading, and a number 5^b of list A or C is used in numbering a station under one of the car-line headings. In this way it is possible for one to determine with ease and convenience how to reach any of the listed destinations from any 105 of the listed points of departure.

The left portion of Fig. 3 shows a portion of an index D of the numbered car-line headings in compact form and may be arranged 110 alphabetically to enable a person readily to ascertain the number of a car-line contained in list B.

10 designates numbers arranged in definite 115 position with relation to certain stations of a given car-line and indicating a crossing or junction with one or more car-lines which may readily be reached from said given car-line at said station. The numbers 10 of the 120 numbered headings 1 of said car-lines are preferably arranged in a row, as shown in Fig. 3, just below the cross-street or station where said junction occurs. This feature of the index assists a person to determine what 125 car-line to take when it is necessary to transfer from one car-line to another and where to make connections with the various car-lines.

In this specification and the appended 130 claims the term "station" means a point of

arrival at or departure from a route of travel whether the same is traversed by cars or not, said points being named and numbered in the order in which they occur along the route.

5 I claim—

1. A directory containing, in combination, a list of numbered route-designating headings, each followed by a list of numbered points on the route, and a list of street-headings each followed by a series of the numbers numbering the route-headings and other numbers, said other numbers being the numbers of the points enumerated under said route-designating headings. 60
2. A directory containing, in combination, a list of numbered route-designating headings, each followed in said list by a series of numbered stations on the route designated; and a list of street-designating headings each followed in said last-named list by a list of house-numbers of the street designated and other numbers under said street-designating headings, said other numbers being numbers numbering the route-designating headings and being arranged in line with said street-numbers. 65
3. A directory containing, in combination, a list of numbered route-designating headings each followed in said list by a series of numbered stations on the route designated; and a list containing a series of places to be located, two numbers being by their position associated with each of said places, one of said numbers being a number used in numbering the numbered route-designating headings and the other number being a number used in numbering the numbered stations under said route-designating headings. 70
4. A directory containing, in combination, a list of numbered route-designating headings, each heading being followed in said list by a series of house-numbers of the streets along which the route extends, said house-numbers being arranged in progressive order from one end of the route and numbering the points where the street upon which the route runs is intersected by cross-streets, said cross-streets being named and provided with a row of numbers consecutively numbering the same; and a list of alphabetically-arranged street-designating headings each followed by a series of house-numbers of the street designated, there being a pair of numbers placed opposite to each of said last-mentioned street-numbers, one of said pair of numbers being a number used in numbering one of the numbered route-designating headings, and the other number of the pair being a number of 75
5. A route-list containing numbered stations on the route, house-numbers of the streets along which the route extends indicating location of cross-streets along the route, names of said cross-streets, and house-numbers of said cross-streets indicating the point of intersection of the route with said cross-streets respectively. 80
6. A directory comprising lists respectively appertaining to definite routes of travel that respectively comprise portions of streets, the same being lists of numbered stations, the stations of each list being named and numbered therein in the order that they occur along the definite route to which such list appertains; house-numbers of said streets indicating in said lists the location of said stations, means at the head of each of said lists to designate the route to which such list appertains; a list of places alphabetically arranged and containing the numbers used in numbering the stations of the first-mentioned lists, said numbers being applied to the places on the last-mentioned list for reference to the first-named list; and means in 85 said last-mentioned list designating the location of said places on the streets where the same are situated. 90
7. A directory containing, in combination, a list of numbered route-designating headings each followed in said list by a series of numbered stations on the route, another list, and numbers applied to points named in said other list; in each instance one of the numbers being a number used in numbering 95 a route-designating heading; and another number being a number used in numbering a station under said heading. 100
8. A directory containing, in combination, a list of numbered route-designating headings each followed in said list by a series of numbered stations on the route, another list C and numbers 5^a, 5^b, applied to points named in said list C, in each instance a number 5^a being a number used in numbering a route-designating heading, and a number 5^b being a number used in numbering a station under said heading. 105

In testimony whereof I have hereunto set my hand, at Los Angeles, California, this 6th day of June, 1905.

CHAS. W. MERRILL.

In presence of—

JAMES R. TOWNSEND,
JULIA TOWNSEND.
